UNITED STATES PATENT OFFICE.

THOMAS E. KING, OF SPRINGFIELD, MASSACHUSETTS.

ARCH SUPPORT.

Application filed November 24, 1926. Serial No. 150,472.

This invention relates to improvements in arch supports.

An object of the invention is to provide an elastic cushion device for supporting the 5 muscles and the metatarsal bones of the foot and, at the same time providing an article that may be easily inserted and removed. It is designed and adapted to fit directly below the arch of the foot and rest 10 on the insole of the shoe.

The purpose of the invention is to provide an elastic pad for supporting the arch portion of the foot of persons who are suffering from fallen or broken arches. One of 15 the advantages of the present invention is the soft and elastic properties of sponge rubber which automatically accommodates itself to the contour of the bottom of the arch portion of the foot. Another advantage 20 is in the covering layers of cotton batting which is compressible like the sponge rubber and will return to its original shape after compression. The outer covering of soft leather is also comfortable. Since the pad is 25 of equal thickness on the opposite sides of its median plane it may be inserted under the foot with either side uppermost.

It is a well known fact that persons suffering from fallen arches require an article 30 that will exert an upward sustaining pressure. The present pad being of a compressible and elastic nature serves to effectually support and relieve the fallen arch.

Broadly considered it comprises a center 35 or core member of sponge rubber of suitable thickness and length. Around this core is wrapped several layers of soft material, as cotton or wool fibres and outside of this material is placed an inclosing casing prefer- 40 ably of leather which is soft and pliable. In other words, the leather casing forms a sac to receive the arch supporting material.

The sponge rubber possesses the characteristic properties of being cellular in struc- 45 ture and very elastic while the layers of cotton or wool are also elastic and are softer than the sponge rubber.

The weight of the foot serves to compress the support and when the weight is relieved 50 it immediately returns to its normal position by reason of its elastic properties thus materially strengthening the muscles of the foot and maintaining the metatarsal bones in their normal position.

55 Referring to the drawings:

Fig. 1 is a side elevational view of the

cushion support partially in section showing the foot in the shoe and the support located in the arch portion of the foot.

Fig. 2 is a plan view of the complete 60 article.

Fig. 3 is a cross sectional view on the line 3-3 of Fig. 2 showing the interior construction.

Fig. 4 is a plan view illustrating a portion 65 of the foot, the shoe in dotted lines, and the location of the support which extends transversely of the foot, and

Fig. 5 is a partial sectional view on the line 5-5 of Fig. 4 through the instep por- 70 tion of the foot, and the pad in full lines.

Referring to the drawings in detail:

1 is understood to designate the foot; 2 the inclosing shoe; 3 designates the pad as a 75 whole which is composed of a center or core member 4 consisting of sponge rubber which possesses the desirable properties of being highly elastic, cellular in structure and comfortable for the wearer.

Wrapped around the core portion 4 are 80 several layers of cotton batting 5 and located outside of the layers of cotton batting is the inclosing casing or sac of soft leather, indicated at 6, which is stitched together as indicated by the dotted lines 7.

Reference is made to Figs. 4 and 5 which 85 show how the arch support is used. It will be noticed that the support or pad extends completely across from one side of the foot to the other and occupies a position under 90 the arch or instep portion of the foot which is clearly shown in Figs. 1 and 4.

Preferably this support is inserted in the shoe outside of the stocking, although if desired, it may be placed inside of the stocking. 95 In either case, the operation of the support is the same.

As shown in Fig. 1, the support pad is in- 100 serted within the stocking, the stocking being indicated by the reference numeral 7'. As shown in Fig. 5 the support or pad 3 is located outside of the stocking.

The supports or pads may be readily made of different sizes and thicknesses to accommodate the individual wearer. The arch 105 supporting device may be cheaply made as it is constructed of inexpensive material, and requires very little labor.

It will be noticed that the support or pad 110 is symmetrical with respect to the horizontal plane or line indicated by the reference numeral 8, Fig. 5, or, in other words the

support is of equal thickness on both sides of this line whereby it may be inserted without reference to either its upper or lower surface.

5 It will be observed from the plan view in Fig. 2 that the support is practically equal in length and breadth.

What I claim is:

An arch support comprising a core member of soft sponge rubber material, layers of 10 cotton batting wrapped around the said core

member of sponge rubber and an inclosing casing or sac of pliable leather stitched together and located outside of the layers of cotton batting, the thickness of the upper 15 and lower parts of the pad being substantially equal with relation to a horizontal plane passing through the center of the pad the whole designed to be reversible and to extend transversely the full width of the in-step of the foot. 20

THOMAS E. KING.
